UNITED STATES PATENT OFFICE.

WILLIAM A. ESTAVER, OF WORCESTER, MASSACHUSETTS.

RUFFLER FOR SEWING-MACHINES.

SPECIFICATION forming part of Letters Patent No. 449,112, dated March 31, 1891.

Application filed June 21, 1890. Serial No. 356,295. (No model.)

To all whom it may concern:

Be it known that I, WILLIAM A. ESTAVER, of the city and county of Worcester, and Commonwealth of Massachusetts, have invented 5 certain new and useful Improvements in Rufflers for Sewing-Machines; and I do hereby declare that the following is a full, clear, and exact description of the same, reference being had to the accompanying drawings and the 10 letters of reference marked thereon, forming a part of this specification, and in which—

Figure 1 represents a side view of a sewing-machine having my improvements combined therewith. Fig. 2 represents a top or plan 15 view of the machine shown in Fig. 1. Fig. 3 represents a front view of the machine shown in Figs. 1 and 2, a portion of the hinged shield or guard plate being broken away to show some of the parts more fully, as will be hereinafter described. Fig. 4 represents a top or 20 plan view of some of the parts with the top or work plate removed, while some of the other parts of the machine are shown in section, as will be hereinafter more fully described; and Fig. 5 represents, upon an enlarged scale, a top or plan view of throats in the 25 work or top plate for the feed, needle, and ruffler points. That part of this top plate in this figure shown is a section, as will be hereinafter described more in detail.

To enable those skilled in the art to which my invention belongs to make and use the same, I will now describe the invention in detail.

35 In the drawings, the part marked A is the bed, B the neck or stationary bar, C the needle-arm or operating-lever, and D the eccentric connection by which the needle-operating lever is driven, of a well-known form of construction of the Willecox and Gibbs sewing-machine.

The main shaft E carries on its front end the looper F, and the feed-arm G, needle-post H⁴, and presser-foot post H³ are all made and 40 operated in the usual manner.

45 In Fig. 4 the top plate A' is removed, while the neck B and eccentric connection D are shown in section, thereby removing all of the upper or overhanging parts of the machine 50 to expose to view more fully the mechanism relating more particularly to my present in-

vention, which has special reference to the ruffling mechanism now to be described.

Upon the main shaft E is arranged an eccentric E' to receive the eccentric-strap F', 55 the upper part F² projecting up and being sawed or cut, as shown at a, so that by means of a screw b, which passes through F², the separated parts can be drawn closer together, as occasion may require, to keep the parts 60 from rattling. Strap F' is also provided with a projecting arm F³, into which is screwed the inner end of connecting-arm A², which has a check-nut A³, whereby said connecting-arm can be locked in any desired position. The 65 outer end of connecting-arm A² is hinged in the upper slotted end of standard B', the lower end B² of which is fitted in a hole formed in the head B³ of a rock-shaft B⁴, fitted to rock in pipe-bearings B⁵ B⁶ in the hanger 70 part B⁶, rigidly fastened to the front upper part of the bed-piece A. Rock-shaft B⁴ is retained in its position longitudinally by a collar b', provided with a set-screw b², whereby its shoulder b³ is held against the end of the 75 pipe-bearing nearest head B³, by which arrangement rock-shaft B⁴ is left free to rock back and forth in its bearings, but is prevented from end-play. Post or standard B' can be set up or down in head B³ and held in 80 such adjusted position by set-screw C⁴.

On the end of rock-shaft B⁴ is fitted an upright arm C', the same being held to the outer end of said shaft by a set-screw c, whereby said arm can be adjusted forward and back, 85 as desired. The upper end of arm C' is slotted, and the outer end of the ruffling-bar G' is pivoted therein, the front underside of bar G' being cut away or beveled off, as seen at d, to form the cam or curved shoulder 90 e, and bar G' is held down upon the friction-roll f on pin e' by a spiral spring f'. Pin e' projects from and is supported in the sliding block g, the outer end g' of which projects through a slot h in the bearing-piece H, the 95 inner end H' being rigidly fastened to the front side of the upright part A⁴ of the base A of the frame by screws h' h'.

An adjusting-screw I passes through and turns loosely in the ends H² H³ of bearing-piece H, a nut k being rigidly fastened to its inner end, while a spiral spring k' is placed

on the outer end between its head I' and the outer end of bearing-piece II; but before the adjusting-screw I is passed through the inner end of bearing-piece H it is screwed through 5 the inner part of sliding block g, and which it supports and keeps in proper position in combination with the slotted bearing-piece H. The inner end of screw-spindle I has a shoulder that bears against the inside of the 10 end H², thus preventing the screw-spindle from moving endwise in one direction, while nut k prevents it from endwise movement in the other direction, and spring k' acts as a friction force to keep spindle I from rattling or being turned too easily from any 15 particular adjusted position of its sliding block g, and which block g is adjusted back and forth to bring the friction-roll f nearer to or farther from arm C' to increase or decrease 20 the fullness of the ruffling, as herein-after explained.

Upon the top of ruffling arm or bar G' is fastened the ruffling-finger G'' by means of the screw m, which passes through slot m' in 25 finger G'', whereby it can be adjusted back and forth to the extent of slot m', as desired, to obtain and get the proper inward throw, and which is to have the ruffling-points n n' just pass beyond the vertical plane of the 30 needle when they reach the inmost extent of their throw or motion, thereby permitting the needle to stitch and fasten the ruffling made.

Between the points n n and n' of finger G'' is 35 a slot o, wide enough to pass the bridge in the top plate A' between the slots cut therein for the proper working of the ruffling-points n n n', which work up through the top plate to act upon the cloth to ruffle the same, point n' 40 working on the inside of needle D', while points n n work on the outside of the needle, with the practical result that the cloth ruffled is kept true and not liable to be turned around the needle, as would be the case if 45 the ruffling were done by the points n n on the outside of the needle alone.

To keep the end g' of sliding block g at all 50 times in close bearings and so that it will not rattle, a gib-piece p is fastened on the inside of the supporting-frame H by screws p', said frame-piece having slots, whereby as any wear takes place it can be raised up against the under side of the end g' of the sliding block-piece g by loosening screws p', and after 55 adjusting gib-piece p, which is made of tempered steel, screws p' are tightened up again and the parts work as well as when first made.

When bar G' is moved inward, its shoulder e, coming in contact with roll f, is raised 60 up, thereby raising the points of ruffling-finger G'' through throats in the top plate A' to engage or catch the ruffling material, which is then moved forward and the ruffle formed to be stitched in place by the needle in the 65 ordinary manner.

In adjusting the ruffling mechanism for use the upright arm C' is to be set in a vertical

position when rock-shaft B¹ is in its extreme inward position, so that said arm C' will not pass beyond a vertical plane when moving 70 forward toward the needle D', and when in this position standard or post B' and connecting-arm A² are to be arranged to stand at right angles to each other, the eccentric E' being set at the time to move strap F' and its 75 arm F³ to their farthest inward points, and this adjustment insures the stopping of the ruffling-finger after its points have just passed the vertical plane of the needle, and the object of making connecting-arm A² adjustable 80 is for the purpose of readily adjusting standard or post B' and its connecting-arm A² into said desired positions, since the angle at which said parts stand to each other can be quickly varied by shortening or lengthening connecting-arm A², and which is done by disconnecting it from the upper slotted end of post B', loosening check-nut A³, and screwing the inner threaded end of connecting-arm A² into or out of projecting arm F³, as may be required to 90 obtain the desired angle, after which check-nut A³ is turned up against the end of arm F³, the parts connected again, and the machine is ready for use. Should the operator thereafter desire to give a greater throw or a 95 less throw to arm C', he can do this by simply raising or lowering post or standard B', as before explained; but this will not materially change the extreme inner throw of finger G''.

I will now explain the advantages of the 100 peculiar motion of my ruffling-finger invented to overcome and obviate the difficulties encountered by ruffling-fingers having a forward, down, and back motion or a down and back motion as soon as the ruffle is formed. 105 Ruffling-finger G'' has a six-motion action—viz., the finger first moves forward until shoulder or cam-surface e on the under side of ruffer-bar G' comes in contact with friction-roll f, when said bar, with its finger G'', is raised 110 up, and by which up motion the finger-points n n' are forced up through their respective parallel throats s s' in top or work plate A', slot o receiving the narrow bridge T in said plate. By this motion the points n n' come 115 in contact with the ruffling material near its edge and press it up against the lower flat surface of spring-plate v, and the said ruffling-finger G'' is now moved forward until 120 its points n n' have passed the needle and by which operation the ruffle is formed and carried into the proper position to be stitched and secured to the edge of the cloth or material which passes over the upper flat and horizontal surface of the separator-plate h², which 125 is supported on the ruffle-guide plate R, the front edge of which is perpendicular, but slants or inclines back from its front inner edge, as fully indicated in dotted lines, Fig. 2. After the needle descends and enters the ruffle to stitch it in place finger G'', with its pointers n n', moves back in nearly a horizontal plane until cam e descends on the 130 front of friction-roll f, when they drop down

- and then move back to the point of starting, having had six motions during the time. By the above motion very loose and open work can be ruffled in a perfect manner—such, for 5 instance, as "Torchon" lace—heretofore deemed unattainable by rapid machinery, one great difficulty having been due to the action of the ruffling-finger used prior to my invention, which had a down and back motion after 10 the ruffle was formed, and which motion of the finger caused its points to catch and draw down the material into the finger-throat in the top plate, thereby spoiling the work. This difficulty is obviated by my invention, 15 in which the finger-points are drawn back in a horizontal plane, or nearly so, until they are entirely free from the threads of the lace, and results from my six-motion action, as above described.
- 20 It will be seen that by moving roll f in or out by means of screw-spindle I finger G'' can be raised sooner or later and the ruffle made more or less full, as may be desired. In the present instance presser-plate v is 25 formed from the same piece of metal as the separator-plate h^2 ; but it may be made from a separate piece of metal and fastened to the end of separator-plate h^2 . T' is the throat for the regular sewing-machine feed, and t 30 the needle-throat.

The shield or guard plate P , which covers and protects the regular sewing-machine feed and stitch-forming mechanisms, is hinged at P' to the upright part A^4 of the bed A of the 35 machine.

The presser-foot post H^3 and the parts connected to its lower end are shown raised to show more clearly the spring or presser-plate v , the front end of which is provided 40 with a needle-throat. As ruffer-finger is well supported in a horizontal position, its finger-points do not cant, but act on the ruffling material, whether open-work or fine glazed cloth, in a true and effective manner, and by 45 having guide R inclined back the edge of the ruffling material is always guided into the proper position.

From the foregoing description it will be seen by those skilled in the art that my invention is simple in construction, while at 50 the same time being of great practical value and utility. First, cog-gearing is not employed, nor are the dirty working parts exposed, thereby avoiding the constant liability of the work being caught and injured and the working parts of the machine broken or thrown out of proper adjustment. Second, the ruffling-finger has a positive motion in both directions forward and back, thereby rendering 55 the ruffling mechanism comparatively certain and noiseless, while at the same time the ruffling is necessarily uniform and very perfect. Third, as the thin end of the ruffling-finger is slotted out and its divided ends so 60 arranged as to work up through separate throats in the top plate of the sewing-machine, one ruffle-point on each side of the

needle and also on each side of a narrow bridge-piece, through the inner end of which is the needle-throat, the action of the ruffling-finger upon the ruffle material is such as to keep 70 said material from working out and around the needle, thereby causing poor work and a loss of much time of the operator in connecting the work and readjusting the materials. 75 Fourth, the inclined guide on top of the top plate, in combination, with the horizontal separator-plate, which is supported on the upper side of the inclined guide-plate, enables the material to which the ruffle is attached to be 80 fed forward in an even and proper manner, since it rests on a level surface, over which it passes during the operation of the machine, while the edge of the ruffling material as it is drawn along by the ruffling-finger is guided 85 gradually into the proper line to be caught by the ruffling-finger and formed into uniform ruffles, to be stitched and secured in place by the needle of the machine. Fifth, the ruffling mechanism does not cover up any of the 90 working parts of the sewing-machine, so as to prevent the same easy access to said parts for examination or repair, as is the case when the machine does not have my ruffling mechanism combined therewith. Sixth, the construction and arrangement are such that it is 95 not necessary to remove, alter, or in any manner modify the front guard or shield plate P , which is pivoted to the front upright part A^4 of the bed of the machine by screw P' , and 100 hence the work is not liable to become soiled or injured by coming in contact with the sewing-machine feed, the hook or looper, or the oily parts of the ruffling mechanism.

In Fig. 2 of the drawings guard or shield 105 plate P is shown broken away to give an unobstructed front view of the sewing-machine feed proper, and also side views of the ruffling-bar G' and ruffling-finger G'' , thereby showing the relative positions of the said 110 parts.

My invention enables even an unskilled operative to do good work, thereby producing the best work at a much less cost, even for help, while the production is largely increased, 115 owing to the capacity of the machine to run at a very high speed.

Having described my improvements in ruffling mechanism for sewing-machines, what I claim therein as new, and desire to secure by 120 Letters Patent, is—

1. The combination, with the main shaft E of the sewing-machine and rock-shaft B^4 , provided with head B^3 , of eccentric E' , strap F' , projecting arm F^3 , connecting-arm A^2 , standard or post B^2 , provided with a bifurcated end B' , upright arm C' , ruffling-bar G' , and ruffling-finger G'' , substantially as and for the purposes set forth.

2. The combination, with the main shaft E and eccentric E' and strap F' , of projecting arm F^3 , head B^3 , provided with set-screw C^4 , adjustable standard B' B^2 , adjustable connecting-arm A^2 , provided with check-nut A^3 ,

rock-shaft B^4 , upright arm C' , and ruffling-bar G' and ruffling-finger G'' , substantially as and for the purposes set forth.

3. The combination, in a sewing-machine and with its bed-plate, of upright arm C' , ruffling-bar G' , ruffling-finger G'' , bar G' being provided on its under side with cam-shoulder e and two horizontal bearing-surfaces, one in front and the other in rear of cam-shoulder e , the latter bearing-surface projecting down below the front bearing-surface the depth of cam-shoulder e , slotted bearing-piece H , with friction-roll f on pin e' , all arranged below the bed-plate of the machine, and rock-shaft B^4 for giving to the ruffling-finger G'' its several described motions, substantially as and for the purposes set forth.

4. The combination, with rock-shaft B^4 , upright arm C' , ruffling-bar G' , and ruffling-finger G'' , of slotted bearing-piece H , sliding block $g g'$, cam-shoulder e , and pin e' , of friction-

roll f and adjusting-screw I , substantially as and for the purposes set forth.

5. The combination, with the bed-plate of a sewing-machine, stitch-forming mechanism, and ruffle forming mechanism, of two parallel ruffler-throats $s s'$ in the top plate, one on each side of the needle-path, narrow bridge T , needle-throat t , ruffling-finger G'' , slot o , and ruffling-points $n n'$, substantially as and for the purposes set forth.

6. The combination, with ruffling-bar G' , ruffling-finger G'' , and mechanism for operating the same, of adjusting-screw I , slotted bearing-piece H , sliding block $g g'$, cam-shoulder e , pin e' , friction-roll f , gib-piece p , and adjusting-screws $p' p'$, substantially as and for the purposes set forth.
